UNITED STATES PATENT OFFICE.

WALTER E. COFFIN, OF CLEVELAND, OHIO, ASSIGNOR TO THE NATIONAL MALLEABLE CASTINGS COMPANY, OF CLEVELAND, OHIO, A CORPORATION OF OHIO.

BUFFER.

1,284,243.

Specification of Letters Patent. Patented Nov. 12, 1918.

Application filed September 1, 1916. Serial No. 117,982.

To all whom it may concern:

Be it known that I, WALTER E. COFFIN, a citizen of the United States, residing at Cleveland, Cuyahoga county, Ohio, have invented certain new and useful Improvements in Buffers, of which the following is a specification, reference being made to the accompanying drawings, in which—

Figure 1 is a plan of a coupler and buffer embodying my improvements, Fig. 2 is a side elevation, Fig. 3 is a front elevation and Fig. 4 is a section partly in elevation. Fig. 5 is a plan of a modified form of my invention and Fig. 6 is a vertical section 15 thereof.

My invention relates to buffers, particularly of the type used on engines and tenders and consists in providing a coupler and a buffer arranged so as to permit the buffer to swing radially with the coupler, and also as a protection both for the coupler head and coupler operating mechanism.

My invention also consists in the construction and arrangement of parts which I shall 25 hereinafter describe and claim.

Referring to the drawings, A indicates an engine coupler, B the pocket in which the coupler is mounted and C the buffer. The coupler A and buffer C are preferably 30 pivoted for lateral movement to the pocket B by the pin 2. The buffer C has at its rear end an arc shaped buffing bearing 3 which bears against the corresponding surface 4 on the coupler pocket. The buffer C ex- 35 tends forwardly of the pin 2 over the top of the coupler head and terminates in a buffing face 5, the ends of which are beveled slightly to the rear so as to permit the buffer to angle more easily with an opposing buffer and also 40 to permit coupling more easily of the coupler A on a curved track with an opposing coupler. Upon the top of the coupler head and about the hole for the operating mechanism is a projection 6 which has at its 45 upper portion outwardly extending horizontally disposed lugs 7 which also extend rearwardly therefrom and coöperate with the inwardly extending and horizontally disposed lugs 8 on the under side of the 50 buffer, and which prevent the buffer from being tipped upwardly and which also serve to guide the buffer laterally and maintain it at all times directly above the coupler. The lugs 7 on the coupler head and lugs 8

on the buffer are extended sufficiently to the 55 rear to maintain their engagement regardless of the wear which may take place in either the buffing bearings of the coupler shank or buffer. The projection 6 and lugs 7 also serve to protect the coupler operating 60 mechanism from injury.

The buffer C is inclined forwardly and upwardly over the coupler and its web 9 has an elongated aperture 10 for the actuating mechanism 11 of the coupler. To prevent the buffer C from being tipped downwardly at its forward end by an opposing buffer and the consequent lifting of the pin 2, the pin is preferably held down by means of a bolt 12 passed through a hole in the 70 lower end of the pin 2. The bolt 12 is inserted through a rectangular aperture 13 in the vertical wall of the extended floor 14 of the coupler pocket, which serves to accommodate the head of the bolt as it is being applied.

In Figs. 5 and 6 I have shown a modified form of my device, in which the coupler head A' is secured to the pocket B' by a pivot pin 2' while the buffer C' is secured 80 to the pocket at a point to the rear of the pin 2' by the pin 2''. Instead of having an interlock with the coupler head as is shown in Figs. 1, 2, 3 and 4, the buffer has an interlock with the pocket casting. The interlock consists in a rearwardly extending arc shaped lug or flange 15 on the upper portion of the coupler pocket which coöperates with a correspondingly shaped forwardly directed lug or flange 16 on the under side 90 of the buffer, for the purpose of holding down the buffer when in engagement with an opposing buffer and passing over an uneven track. The web of the buffer has an elongated aperture 17 for the coupler operating mechanism which permits the coupler head to swing radially in either direction without interference from the buffer.

It has been found that when an engine is coupled to a passenger car, there is a 100 liability of having the passenger buffer ride up over the engine coupler and thereby injure a switchman standing on the buffer beam. There is also a likelihood of the passenger buffer injuring the lock lifting mechanism of the engine coupler. By the use of my invention these difficulties are avoided, 105 since the buffer will always engage the op-

posing buffer and thereby serve as a protection for the switchman and as a guard for the lock lifting mechanism.

The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

1. In buffering mechanism for engine couplers, a coupler and a buffer pivoted for lateral movement to an engine pocket, said coupler having on its top an upward

projection having horizontally extending flanges, the buffer overlying the coupler and having depending members engaging said flanges, said flanges and members comprising means for moving coupler and buffer together laterally in unison.

2. In buffering mechanism for engine couplers, an engine pocket having a coupler and a buffer pivoted thereto, said buffer having a horizontally extending flange on its under side engaging a horizontal extension on one of the other members, said flange and extension comprising means for holding the buffer from upward movement during buffering.

WALTER E. COFFIN.
